UNITED STATES PATENT OFFICE.

JAMES H. R. TALLEY, OF SHELDON, ASSIGNOR OF ONE-HALF TO CHARLES P. BARNES, OF LAMAR, MISSOURI.

DUMPING-CAR.

SPECIFICATION forming part of Letters Patent No. 352,498, dated November 9, 1886.

Application filed April 15, 1886. Serial No. 198,921. (No model.)

To all whom it may concern:

Be it known that I, JAMES H. R. TALLEY, a citizen of the United States of America, residing at Sheldon, in the county of Vernon and State of Missouri, have invented certain new and useful Improvements in Track-Laying Machines and Dumping-Cars; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention has reference to dumping-cars; and it consists in the improvements hereinafter fully described, whereby provision is made for interchangeably using the dumping-platform either with a truck to discharge the entire load at one side, or with a truck adapted to permit the free pivotal movement of the sections composing the platform, to dump the entire load either between the track-rails or equally on either side of said track. By my 25 improvements the dumping of either a part or all of the load may also be effected at right angles to the direction of the track.

In the accompanying drawings, forming part 30 of this specification, Figure 1 is an end perspective view of my improved dumping-car, representing the same arranged for dumping the entire load at either side, the platform in said view being shown in a tilted position. Fig. 2 is a side perspective view of the construction shown in Fig. 1, the platform being 35 represented as restored to its normal position. Fig. 3 is a transverse sectional view representing my improvements arranged for dumping the load either between the track-rails or a part on either side of the same; and Fig. 4 is a detail perspective view of the device used 40 for turning the car at right angles to the direction of the track, in order to remove the truck from the track.

45 The main frame of the machine consists, in part, of side bars, A A, each of which has its respective ends extended and shaped to form handles for moving the car along the track. A series of cross-beams, B B, form the transverse parts of the frame, and are each cut away 50 at their extremities to present shoulders a,

which bear upon the upper faces of the side bars, A. The bearings b b for the axles c c are secured to the bars A A in any suitable manner.

When it is desired to dump the entire load at either side of the car, I introduce between the truck-frame and the platform the devices shown in Figs. 1 and 2. In said figures, C C refer to a series of bars, each of which has its under face converged toward its center, so as to present a central bearing portion, which rests upon the upper face of the beam B below, so that said bar C may be readily tilted on said beam in either direction. A metal yoke, 65 d, is secured centrally on each bar C, at either side of the same, and has its horizontal portion extending beyond the upper face of said bar and perforated for the passage of a pin or bolt, d', upon which turns a roller, e. At or 70 near each end of each bar C is located an iron plate, d'', which has a vertical portion extending above the upper face of the beam C, and, in conjunction with the projecting portion of the iron on the other side, presents a bracket, 75 in which is journaled another roller, e'. Each of the bars C is pivotally retained in position upon its beam B below by means of a vertical iron, D, which is bolted to the face of the beam B and pivotally secures the bar C above by 80 means of a bolt, d''. The upper portion of the iron D is bent outwardly and then vertically, so as not to interfere with the yoke secured on the bar C while the latter is oscillating. The upper end portion of the iron D has a depression, 85 with which engages a pin, d', located on one of the guide-rails of the platform. Pivotally secured to the outer end of this bar C is a depending link, D', which is adapted to engage the projecting portion or shouldered portion a of the beam B beneath, and thus permitting the bar C to be movably secured in position upon the beam B, as fully shown in Fig. 2.

The platform proper of the car consists of 90 two longitudinal sections, each of which is about one-half the width of the platform area, and is centrally pivoted upon a longitudinal rod, E, which extends the entire length of the platform, and has its ends seated in the end 95 portions, E', which are independent of the platform.

Each of the platform-sections is re-enforced on its end-face by a series of short transverse battens, E'', which are intersected by another series of battens, E''', extending at right angles thereto, the latter battens being so disposed as to present between their adjacent faces a series of grooves or recesses, in each of which is seated a guide-rail, E'', which is of such length as to extend the entire transverse width of the platform, and is so located that when the platform is in the position represented in Fig. 2 the said guide-rail rests upon the rollers e and e' below. The end portions, E', have each a series of brackets, f, which are bent to present bearing-loops for a series of bent rods, f', each having its projecting portion turned at right angles, in order that said portion may be readily turned under the sections of the platform, as shown in Figs. 1 and 2, to prevent any tilting movement whatever of said sections.

In practice, after the platform has been loaded and the car moved to the point where it is desired to dump the load, it is only necessary to detach the links C' from the shoulders a, and then by drawing on the rope f'' move the platform a short distance on the rollers, which, by reason of the shifting of the weight of said platform sliding to one side of the center, will cause the bars C to be thrown to the position indicated in Fig. 1, causing the rollers to assume an inclined position, from which the car-platform readily slides and is dumped. In effecting the foregoing operation it is desirable, however, that the longitudinal center of the platform should not pass beyond the limit of the car, and for this purpose each of the inner irons, d'', is extended upwardly and curved to present a hooked portion, g, which, when the center of the platform reaches the side limit of the car, engages the rods g', which pass transversely through the guide-rollers, and secures them rigidly relative to each other. The engagement of said hooked portion g with said rod g' prevents any further movement of the platform from the car, and by reason of the center engagement of the platform the rope g'' may be readily operated to restore the platform into nearly a horizontal position, after which it may be drawn back upon the bars C.

By the arrangement previously described it will be noted that but a minimum amount of power is exerted to shift the platform to the side of the car, owing to the automatic inclination of the bars C, and the engagement of the hooked portion g with the rod g' effects the inclined horizontal movement of said platform, thereby causing it to swing to a nearly vertical position and dump the load close to the side of the track. In order to prevent accidental tilting of the truck, I have secured to each of the beams A a short section of chain, g''', to the end of which is attached a hooked plate, g'', which engages with the under side of the track-rail.

When it is desired to effect the dumping between the rails, or a portion of the load on

either side of the same, the platform is removed from the truck, (represented in Figs. 1 and 2,) and the guide-rails E'' removed in series 70 from their respective grooves. Then by manipulating some of the bolt-connections the entire series of bars C, with their yokes and rollers, may be next moved in series, and upon each end beam B are mounted two conical standards, G G, each of which is centrally braced by an iron bar, G', which extends up under the upper portion of the standard, and is recessed to form a bearing for one of the rods E E. It will now be understood that by manipulating the several catches f', so as to withdraw their horizontal portions from beneath the platform-sections, the latter may be moved upon their pivotal bearings, so that their adjacent inner edges may be moved downward 85 so as to dump the entire load between the track-rails. Of course by moving their outer edges downward, after having removed their side flanges, G'', which may be adjustable in any manner, an equal part or portion of the 90 load may be deposited on either side of the track-rails.

Should it be desirable to remove the entire truck from the track, the device illustrated in Fig. 4 is employed, consisting of the beam H, 95 which is contracted from its center to either end, and has bearing in its end portions, rollers h, which are housed by brackets h', the central portion of the beam H being embraced by a metallic yoke, h'', which is spread at its lower 100 part for the top of the disk H', which has a central groove, h''', on its under face. By tilting one end of the truck and placing the device illustrated in Fig. 4 beneath the same, so that the central portions of the said bars H 105 rest upon the rollers h, and one of the ties of the track rest within the recess h' when the truck is restored to a horizontal position, the height of the said device is such that all four wheels will be lifted from the rails a sufficient 110 distance to permit the truck and beam H to be rotated on the disk H', to turn the car to a position at right angles to the direction of the track.

It will be readily appreciated that the arrangement of the intermediate parts between the platform and the truck proper is such that they may be readily transposed for the several purposes hereinbefore stated without involving any considerable amount of time or labor, and that all of the parts are of simple and durable form and best calculated to stand the jar and strain usually incurred by this class of cars.

I claim—

1. The combination, in a dumping-car, of a truck, a series of tilting beams pivoted thereon and provided with hooked portions g, and a platform adapted to slide on said beams, and having a rod, g', to engage said hook portions, substantially as set forth.

2. The combination, in a dumping-car, of a car-truck, a series of tilting beams pivoted thereon, a platform adapted to slide on said

beams, and devices, C', for locking said beams against tilting, substantially as set forth.

3. The combination, in an interchangeable dumping-car, of a car-truck, intermediate shifting devices provided with rollers and platform consisting of two longitudinal pivoted sections, and a series of guideways, E', detachably secured to said platform, substantially as set forth.

4. In combination with a dumping-car, the

tilting device consisting of grooved disk H' and beam H, pivotally mounted thereon, substantially as set forth.

In testimony whereof I affix my signature in presence of two witnesses.

JAMES H. R. TALLEY.
